UNITED STATES PATENT OFFICE.

LLOYD S. ALLEN, OF NEW YORK, N. Y.

LANDING-GEAR FOR AEROPLANES.

1,296,734.

Specification of Letters Patent. Patented Mar. 11, 1919.

Application filed August 10, 1916. Serial No. 114,131.

To all whom it may concern:

Be it known that I, LLOYD S. ALLEN, a citizen of the United States, residing at New York, N. Y., have invented certain new and useful Improvements in Landing-Gear for Aeroplanes, of which the following is a clear, full, and exact description.

This invention relates to an improvement in aeroplanes, and particularly in the landing gear thereof, and has for its objects the provision of means whereby the landing gear may more efficiently check the progress of the machine when on the ground, but to retard the machine as little as possible when in the air.

A further object is to provide a landing gear which may be folded up against the body of the aeroplane when in flight and which is easily adjustable by the operator so as to be held both in its lower position for alighting on the ground, and in its upper folded position for traveling in flight.

A further object is to provide braking means in combination with the landing frame, which will be automatically applied by the pressure of the machine on the ground to exert a checking effect both at the fore part and at the after part of the machine. The application of such a braking means thus tends to prevent the machine from plunging its nose into the ground due to sudden checking forward, and also from throwing its head upwardly due to too sudden checking of the after part of the machine.

Further objects and advantages of construction will become apparent from the following detailed description of the preferred embodiment of my invention, which preferred embodiment is illustrated in the accompanying drawings in which—

Figure 1 is a side elevation of so much of an aeroplane as is necessary to show my improvement attached thereto;

Fig. 2 is a detail front elevation of the landing frame looking in the direction of arrow A in Fig. 1;

Figs. 3 and 4 are detail vertical sections taken at right angles to one another of the brake for the landing wheels;

Fig. 5 is a partial plan view of the aeroplane body showing the controlling devices;

Fig. 6 is an enlarged cross section of the elastic retaining band for holding the landing frame in adjusted position through line 6—6 of Fig. 8;

Fig. 7 is a detail section showing the position of the retaining band when holding the landing frame down;

Fig. 8 is a detail top view of the retaining band;

Fig. 9 is a detail of the brake prevention device, and

Fig. 10 is a detail section of the upper end of a slidable extension from the landing frame.

Referring more particularly to the drawings, 1 indicates the usual body portion of an aeroplane having the usual propeller 2 and rear steering and elevating rudders 3 and 4. The showing of the supporting planes has been omitted as being unnecessary for an understanding of the present invention. Mounted at the fore part of the body 1 is a landing frame comprising a rearward extension 5 pivoted at 6 upon the body, and a forward extension 7 slidably guided in the body 1, said extension preferably being curved in form, the radius of which has its center at 6. Both the rear extension 5 and the forward extension 7 are preferably formed of double spars attached to the axle 8 of the landing frame (see Fig. 2), and said vertical spars 7 are preferably extended slightly below the axle at 9, and trussing wires are connected from said axle to the spars 7 and 9 for strengthening purposes. At the outer ends of the axle 8 are mounted the usual landing wheels 11.

The upper end of each extension 7 passes within the body 1 and is slidably engaged with guides 12 in the bottom wall of said body, as shown in Fig. 7. The upper end of each extension 7 also is provided with a curved socket 13 cut away at one side. Upon each side wall of the body 1, as shown in Figs. 5 and 8, is an elastic retaining band 14 fastened at each end to eyes 15 and 16 riveted in said body 1. The retaining band 14 is preferably formed of a series of rubber bands bundled together as shown in Fig. 6. An embracing strap or collar 17 for said band is connected to a controlling cord 18 which leads to a lever 19 located adjacent the operator's seat 20, whereby each retaining band 14 may be pulled laterally toward the center of the machine when desired. Each retaining band tends to lie in the position shown in Figs. 5, 7 and 8 due to its elasticity, and when the extensions 7 are drawn down as shown in Fig. 7, the retaining bands 14 will move into the sockets 13 of said ex-

100

105

110

tensions 7 and thus hold the extensions in their downward position. A pin 21 on each extension 7 acts as a stop against the guide 12 to limit the downward position of said extension 7.

Elevating cables 22 lead from hand-operated drums 23 adjacent the operator's seat over pulleys such as 24, and are connected to the axle 8 of the landing frame, so that by 10 operation of said winding drums 23 by the handle 25 the landing frame may be elevated and thus folded against the body of the machine.

The operation of the landing frame is as follows: Assuming it to be in its lower position shown in Fig. 1. If then it is desired to elevate the frame so as to fold it against the aeroplane body, the operator first swings lever 19 so as to pull on cables 18 and stretch 15 the retaining bands 14 laterally away from their position within the sockets 13 of each extension 7. The operator then winds the drum 23 by handle 25, which pulls on the cables 22 and elevates the landing frame. 20 Since each extension 7 passes up inside of the retaining bands 14 so as to keep them in stretched outer position, the pressure of the retaining band against each extension 7 is sufficient to hold said retaining frame in its 25 upper position. In order to drop the frame, the operator merely pulls each retaining band 14 away from its frictional engagement with each extension 7, and thus the frame is allowed to drop by gravity and 30 each retaining band is then released to rest 35 within its socket 13.

Each landing wheel 11 is preferably provided with braking means, such as an internal brake 26 as indicated in Figs. 3 and 4. 40 An operating cable 27 leads from each brake upwardly around a pulley 28 adjacent the pivot 6, and then rearwardly to a ring 36 (see Fig. 5). From the ring 36 a cable 27' leads rearwardly around a return pulley 29 45 (see Fig. 1) and is connected to the upper end of a skid 30, pivoted at 31 at the after part of the machine. Interposed in cable 27' is a spring 32 and a turn buckle 33 for taking up the slack in said cable. It will 50 be obvious from this construction that whenever the tail skid 30 is pressed against the ground by the operator, for instance by the operation of the elevating rudders 4 so as to cause a depression of the tail of the machine, 55 then the swinging of said tail skid 30 causes tension to be applied on the brake cables 27', 27 for applying the brakes 26 on the wheels 11. This causes a checking of the progress of the machine both at the forward and after 60 parts thereof, which is very desirable to prevent pitching of the machine either up or down when coming to a stop.

Brakes 26 are provided with the usual releasing springs 34, which of course are only 65 of sufficient strength to release the brakes

when no pressure is applied thereto, but in order to release the brakes even against the pressure of the tail skid 30, and to prevent the application of the brakes whenever desired, I have provided a supplemental hold-back cable 35 connected to ring 36, said hold-back cable leading forward to a lever 37 (see Fig. 9). Lever 37 is provided in turn with a holding pawl 38 adapted to engage a notch in a fixed block 39. Whenever 70 foot-lever 37 is pushed forward by the operator, the cable 35 will cause a slack in the cables 27, which are forward of the ring 36, and any tension upon the rear cable 27' due to the pressure of the tail skid is transmitted 80 through said spring 32 directly to the foot-lever 37 instead of to the brakes 26, and consequently said brakes will not be operated. The holding pawl 38 of lever 37 may of course be disengaged by its foot-pedal 40 85 and thus allow the brakes 26 to again be operated by the pressure of the skid 30. The use of the brake prevention device 37 is desirable when starting from the ground, because at this time the tail of the machine 90 resting on the ground might cause a depression of the skid 30 to cause an application of the brakes. Also it is desirable to have the brake prevention device in operation when the machine first strikes the 95 ground in alighting, because the checking shock would be too great if the wheels hit the ground locked fast against rotation. It is therefore preferable to have the wheels hit the ground while free to rotate and then 100 gradually apply the brake thereto by depressing the tail of the machine.

It is obvious that various modifications and changes may be made in the details of my construction without departing from the 105 spirit of the invention as embodied in the claims.

What I claim as new is:—

1. The combination with an aeroplane body, of a landing frame arranged to fold up against the same, said frame having landing wheels carried at the lower portion thereof and having an upward extension pivoted to said aeroplane body, and another upward extension slidably connected with 110 said aeroplane body, guides on said aeroplane body for said slidably extension, resilient devices for holding said slidably extension in various adjusted positions, and means under the control of the operator for 115 raising and lowering said landing frame.

2. The combination with an aeroplane body, of a landing frame arranged to fold up against the same, said frame having landing wheels carried at the lower portion 125 thereof and having an upward extension pivoted to said aeroplane body, and another upward extension slidably connected with said aeroplane body, guides on said aeroplane body for said slidably extension, and 130

- rubber bands arranged to rest against the upper ends of said extensions when the frame is lowered and against the sides of said extension when the frame is raised for holding the same in various adjusted positions, and means under the control of the operator for raising and lowering said landing frame. 5
3. The combination with an aeroplane body, of a landing frame arranged to fold up against the same, landing wheels carried on said frame, braking means for said wheels, a tail skid mounted on said aeroplane body, and means operated by the pressure of said tail skid on the ground for applying the braking means to said landing wheels. 10
4. The combination with an aeroplane body, of a landing frame arranged to fold up against the same, landing wheels carried on said frame, braking means for said wheels, said frame having one extension pivoted to said aeroplane body and another extension slidably connected with said body, means under the control of the operator for raising and lowering said landing frame, a tail skid mounted on said aeroplane body, and means operated by said tail skid for applying the braking means to said landing 20 wheels. 25
5. In combination with an aeroplane body, of a landing frame having landing wheels carried thereon, braking means for said wheels, a tail skid on said aeroplane body, and means operated by the full pressure of said tail skid upon the ground for automatically applying said braking means to said landing wheels. 30
6. In combination with an aeroplane body, of a landing frame having landing 40
- wheels carried thereon, braking means for said wheels, a tail skid on said aeroplane body, and means operated by the pressure of said tail skid upon the ground for applying said braking means to said landing wheels, 45
7. In combination with an aeroplane body, of a landing frame having landing wheels carried thereon, braking means for said wheels, a tail skid on said aeroplane body, means operated by the pressure of said tail skid upon the ground for applying said braking means to said landing wheels, 50
- and means under the control of the operator for preventing the application of said braking means by the pressure of said tail skid. 55
8. In combination with an aeroplane body, of a landing frame carrying landing wheels thereon, braking means for said landing wheels, a tail skid mounted on said aeroplane body, connections from said tail skid to said braking means, including a flexible cable and a resilient member whereby the pressure of said tail skid on the ground causes an application of said braking means, means under the control of the operator for preventing the application of said braking means by said tail skid, comprising a cable 60 working in opposition to said first named cable, and locking means for holding said last named cable in adjusted position. 65

Signed at New York, N. Y., this 26th day of June, 1916.

LLOYD S. ALLEN.
